UNITED STATES PATENT OFFICE.

OSCAR C. ENGEBRETSON, OF GARRETSON, SOUTH DAKOTA.

ATTACHMENT FOR PITCHFORKS.

1,072,592.

Specification of Letters Patent.

Patented Sept. 9, 1913.

Application filed November 3, 1911. Serial No. 658,416.

To all whom it may concern:

Be it known that I, OSCAR C. ENGEBRETSON, a citizen of the United States, residing at Garretson, in the county of Minnehaha, 5 State of South Dakota, have invented certain new and useful Improvements in Attachment for Pitchforks; and I do hereby declare the following to be a full, clear, and exact description of the invention, such as 10 will enable others skilled in the art to which it appertains to make and use the same.

This invention relates to new and useful improvements in attachments for pitch forks.

15 An object of this invention is the provision of a device of this character which is adapted to be applied to the prongs of a pitch fork for the purpose of increasing their diameter and converting the same into 20 an implement for use in handling corn stalks or the like.

Another object of this invention is to improve and simplify devices of this character, rendering them comparatively simple 25 and inexpensive to manufacture, reliable and efficient in use and readily operated.

With the above and other objects in view, this invention resides in the novel features of construction, formations, combinations 30 and arrangements of parts to be hereinafter more fully described, claimed and illustrated in the accompanying drawings in which:—

Figure 1 is a front elevation of one frame of my improved pitch fork. Fig. 2 is a rear 35 elevation thereof. Fig. 3 is a longitudinal sectional view taken on the line 3—3 of Fig. 1. Fig. 4 is a transverse sectional view taken on the line 4—4 of Fig. 1. Fig. 5 is a similar view taken on the line 5—5 of 40 Fig. 1. Fig. 6 is a side elevation illustrating a modified form of my invention, and Fig. 7 is a transverse sectional view taken on the line 7—7 of Fig. 6.

Referring to the accompanying drawings 45 by similar characters of reference, the numeral 10 designates generally a pitch fork of the usual construction which comprises a head 11 formed at one edge with a socket 12 for the reception of a handle 13 and at 50 its opposite edge with a plurality of diverging prongs 14.

A plurality of outer and intermediate

sleeves 15 and 16 are slidably located upon the prongs 14 and are provided at their lower terminals with rounded ends 17. The 55 opposite ends of the sleeves 15 are formed with curved channel spring extensions 18 which engage the sides of the head 11 while the sleeve 16 is provided with a spring extension 19 which terminates flush with the 60 extensions 18. The extensions 18 and 19 are formed with registering grooves 20 for the reception of a retaining member 21 which is adapted to hold the extensions against displacement thereby preventing 65 disengagement between the prongs 14 and the sleeves 15 and 16.

Referring more particularly to Figs. 6 and 7 of the drawings, the extensions 18 and 19 are omitted and the sleeves 15 and 16 70 are provided with contacting ears 22 which are aliningly apertured as at 23 for the reception of a suitable locking member 24 which holds the converged ends of the sleeves 15 and 16 rigidly with respect to 75 each other to open the prongs 14 by their diverging relation with respect to each other.

From the foregoing disclosures taken in connection with the accompanying drawings 80 it will be manifest that an attachment for pitch forks is provided for which will be securely held thereon against any undesired displacement, and which will fulfill all of the necessary requirements of such a 85 device.

Having thus fully described this invention what I claim as new and desire to protect by Letters Patent, is:—

1. The combination with a pitch fork, of 90 a plurality of sleeves located upon the prongs thereof, extensions formed upon said sleeves conforming to the shape of the head of the pitch fork, and a means engaging the extensions for preventing their displacement from the pitch fork.

2. The combination with a pitch fork, of 95 a plurality of sleeves located upon the prongs thereof, spring extensions formed upon the sleeves and conforming in shape 100 to the head of the pitch fork, said extensions being provided with registering grooves and locking means engaging said registering grooves.

3. The combination with a handle, and a head carried thereby and provided with a plurality of prongs, of a tubular member engaging each prong, and means connecting said members at their upper ends and holding the same in operative position on the prongs.

In testimony whereof, I affix my signature, in presence of two witnesses.

OSCAR C. ENGEBRETSON.
